[57] **CLAIM**

The ornamental design entitled combined handicap door sill and threshold, as shown and described.

DESCRIPTION

FIG. 1 is a fragmentary view of my new combined handicap door sill and threshold design;

FIG. 2 is a right side view of my new design, the left side view being a mirror image thereof;

FIG. 3 is a top plan view thereof, the combined handicap door sill and threshold has been broken in the center for ease of illustration;

FIG. 4 is a rear view thereof;

FIG. 5 is a bottom view thereof; and,

FIG. 6 is a front view thereof.
